US0D1060676S

(12) **United States Design Patent** (10) **Patent No.:** **US D1,060,676 S**
(45) **Date of Patent:** **** Feb. 4, 2025**

(54) **HUMERAL IMPLANT**

(71) Applicant: **HOWMEDICA OSTEONICS CORP.**, Mahwah, NJ (US)

(72) Inventors: **Kevin P. Knox**, Fort Wayne, IN (US); **Austin Wyatt Mutchler**, Warsaw, IN (US); **Shawn M. Gargac**, Fort Wayne, IN (US); **Alexander Paul Wolfe**, Fort Wayne, IN (US); **David R. Stump**, Columbia City, IN (US)

(73) Assignee: **HOWMEDICA OSTEONICS CORP.**, Mahwah, NJ (US)

(**) Term: **15 Years**

(21) Appl. No.: **29/871,678**

(22) Filed: **Feb. 24, 2023**

(57) **CLAIM**

The ornamental design for a humeral implant, as shown and described.

DESCRIPTION

FIG. 1 is a top of a humeral implant of our design; FIG. 2 is a bottom perspective view thereof;

FIGS. 3-6 are left, right, front, and back side views, respectively, thereof;

FIG. 7 is a top view thereof; and

FIG. 8 is a bottom view thereof.

FIG. 9 is a top perspective view of another humeral implant of our design;

FIG. 10 is a bottom perspective view of the humeral implant of FIG. 9;

FIGS. 11-14 are left, right, front, and back side views, respectively thereof;

FIG. 15 is a top view thereof; and

FIG. 16 is a bottom view thereof.

FIG. 17 is a top perspective view of another humeral implant of our design;

FIG. 18 is a bottom perspective view of the humeral implant of FIG. 17;

FIGS. 19-22 are left, right, front, and back side views, respectively thereof;

FIG. 23 is a top view thereof; and

FIG. 24 is a bottom view thereof.

FIG. 25 is a top perspective view of another humeral implant of our design;

(Continued)

FIG. 26 is a bottom perspective view of the humeral implant of FIG. 25;
 FIGS. 27-30 are left, right, front, and back side views, respectively thereof;
 FIG. 31 is a top view thereof; and,
 FIG. 32 is a bottom view thereof.

1 Claim, 20 Drawing Sheets
